UNITED STATES PATENT OFFICE

159,808

CANASTA SCORER

William Clair Haring, Wichita, Kans.

Application December 10, 1949, Serial No. 6,547

Term of patent 14 years

(Cl. D34—5)

To all whom it may concern:

Be it known that I, William Clair Haring, a citizen of the United States, residing at Wichita, State of Kansas, have invented a new, original, and ornamental Design for a Canasta Scorer, of which the following is a specification, reference being had to the accompanying drawing, forming a part hereof.

Fig. 1 is a top plan view of a canasta scorer showing my new design; and

Fig. 2 is a sectional view thereof taken on the line 2—2 of Fig. 1.

I claim:

The ornamental design for a canasta scorer, as shown.

WILLIAM CLAIR HARING.
